CLAIM

The ornamental design for the toothbrush with fluid jet assembly, as shown and described.

DESCRIPTION

FIGS. 1-2 are first and second perspective views of the toothbrush with fluid jet assembly in accordance with the principles of the present invention;

FIG. 3 is a front plan view of the toothbrush with fluid jet assembly;

FIG. 4 is a rear plan view of the toothbrush with fluid jet assembly;

FIGS. 5-6 are first and second side plan views of the toothbrush with fluid jet assembly; and

FIG. 7 is a top plan view of the toothbrush with fluid jet assembly; and,

FIG. 8 is a bottom plan view of the toothbrush with fluid jet assembly.

The portions of the figures shown in broken lines are for illustrative purposes only and form no part of the claimed design.
